UNITED STATES PATENT OFFICE.

CHARLES E. MOORE, OF LOS ANGELES, CALIFORNIA.

SAFETY FLASH-LIGHT APPARATUS FOR ELEVATORS.

No. 885,942.

Specification of Letters Patent.

Patented April 28, 1908.

Application filed September 3, 1907. Serial No. 391,280.

To all whom it may concern:

Be it known that I, CHARLES E. MOORE, a citizen of the United States, residing in the city of Los Angeles, county of Los Angeles, 5 and State of California, have invented a certain new and Improved Safety Flash-Light Apparatus for Elevators, of which the following is a specification.

This invention relates to the provision, on 10 the car or cage of an elevator system, of an electric lamp to be automatically lighted when the elevator car is brought to a stand still, and to be automatically extinguished when the elevator is put in motion, the light 15 being so arranged as to reflect upon the threshold of the landing, showing a person about to alight from or enter the car, whether or not the floor of the car or cage is level with the landing floor, thus avoiding accidents due 20 to the stopping of the car above or below the floor of the landing.

The invention consists in providing an electric lamp in such position as to throw its rays of light directly across the landing, the 25 lamp being preferably provided with a reflector, so as to concentrate its rays upon the landing. This lamp is connected in circuits which are completed and broken alternately by the operation of the operating arm or 30 lever by which the motion of the car is controlled.

The invention consists further in the constructions and combination of parts herein-after set forth and particularly specified in 35 the claims and will be more readily understood by reference to the accompanying drawings forming a part of this specification, and in which

Figure 1 is a cross-section of an elevator 40 car or cage provided with my flash light apparatus. Fig. 2 is a diagrammatic view of the circuit making and breaking means, the same being shown on an enlarged scale. Fig. 3 shows a slightly modified arrangement of 45 the electric circuits particularly adapted for use on hydraulic or other lever controlled cars, in which the control lever is brought to a vertical position when the car is stopped.

As shown in the drawings, 2 represents an 50 electric lamp which may be arranged at any convenient point at or near the floor of the car or cage, or in any other preferred position, so that the rays of the lamp may be thrown upon the threshold of the landing when the 55 car is brought into proximity with the landing and stopped. This lamp is provided

with a reflector 3 of the ordinary or any preferred construction.

When my invention is applied to a car operated by an electric motor with an electrical control switch in the car, I prefer to employ the electric connections for the flash-light, substantially as shown in Figs. 1 and 2 where I have indicated two pairs of circuit makers and breakers adapted to be operated 60 by the switch arm 4 of the controlling switch. These circuit makers and breakers 5, 6 may be of any ordinary or any preferred construction. As shown, they consist of a plug 7 having an annular shoulder 8 on the inner 70 side of which a spring 9 is adapted to bear and normally throw the plug or rod 7 out so that the circuit between the metal contacts 10 and 11 is broken. These contacts are preferably secured to strips of insulation 12 75 fastened to the body of the elevator car or to the switch-board of the car, as desired, and plates 13 are secured to the face of the part carrying the contact plugs 5, 6. Each of these plates 13 is provided with an opening 80 through which the head of the contact plug is adapted to extend, the shoulder 8 preventing the spring 9 from ejecting the contact plug from its socket. Preferably the outer ends or heads of the contact plugs 5, 6 are 85 rounded, as shown.

In electrically operated elevator systems the car is ordinarily provided with a controlling switch having contacts at one side to operate the magnetic control, which in 90 turn actuates the motor switch so as to complete the motor circuit and cause the motor to be actuated in a direction to carry the car up, and is provided with contacts at the other side so as to actuate the motor switch 95 to cause the motor to be actuated to permit the car to descend, a control-circuit switch-arm or lever, as indicated at 4 Fig. 1, being used to close either the "up" or "down" circuit through these contacts. I prefer to 100 embody my invention upon a car by providing two pairs of contacts, one in connection with the "up" contacts of the control switch, and one pair in connection with the "down" contacts of the control switch, and 105 have illustrated these as arranged at the sides of the switch arm 4, which is shown in vertical position in Fig. 1.

14 indicates a battery or source of electrical energy, and may be either a dry or storage 110 battery, or, if desired, be connected in a derived circuit from the car control switch cir-

cuit, as desired. From this source of electrical energy 14 the circuit is traced through wire 15 to the contact 11, from the contact 10 through wire 16, magnet 17, wire 18 to battery. 5 It will be noted that the circuit is broken between the contacts 10, 11 until the circuit maker or plug 5 is pressed inward to make contact with the ends of the plates or contacts 10, 11. The circuit is then completed 10 and the magnet 17 energized to draw the circuit closer 19 inward between the contacts 20, 20' of the light circuit, closing the light circuit through the circuit wires 21, 21', this light circuit being connected, as indicated, with a suitable source of electrical energy, which may be by a circuit from any suitable source of electrical energy, or from a storage battery.

When the lever arm 4 is moved toward a 20 vertical position so as to pass from the plug 5 and release the same, then pass on to the plug 6, pressing the point thereof between the contacts 10 and 11 the breaking circuit is completed and the magnet 22 energized 25 to draw up the locking detent 23 allowing the circuit closer 19 to pass away from the contacts 20, 20' of the light circuit. The circuit of the magnet 22 is traced from the battery or source of electrical energy 14 30 through the wire 24 and contact 11, plug 6, contact 10, wire 25, magnet 22 and return wire 26 to the battery.

It will be noted that the detent 23 is provided with a shoulder or off-set which engages back of the circuit closer 19 positively holding the circuit closer 19 in contact with the contacts 20, 20', until the breaker magnet has been energized to draw the detent up and allow the circuit closer to withdraw. 35 40 This circuit closer 19 may be provided with a conical contact point as shown, and depend upon the spring pressure of the spring contact 20, 21 to break the contact, or, if desired, a spring may be employed in connection with the circuit closer 19 to exert spring pressure to retract the closer 19 when the detent 23 is drawn up by the magnet 22.

Assuming that the foregoing description is applied to the pair of contacts 5, 6 provided in connection with the control switch on the car so as to be in position to be operated when the elevator car is traveling in an upward direction, I provide a similar pair of contacts indicated as 5', 6' in Fig. 1 connected in a similar manner as before described, so that when lever arm 4 is thrown to the right to allow the car to move downward the lamp 3 is extinguished by the arm 4 coming in contact with the contact 6', and 55 60 when the downward direction of the car is interrupted and the car brought to a standstill the arm or lever 4 strikes the plug 5', completing the circuit through the magnet 17, drawing the circuit closer 19 into place to close the lamp circuit.

When my invention is applied to hydraulic elevators or to elevators of a type having a lever or arm in which the car is brought to a stop only when the operating arm or lever is in vertical position, it is only necessary to 70 provide one plug 5, as indicated in Fig. 3, a circuit breaking plug 6 and magnet 22, with their circuit connections being provided in position to be operated by the operating lever when thrown into position to start the car 75 upward or downward. It is thus seen that provide electrically controlled means for lighting and extinguishing the threshold flash light whenever the car-switch lever is thrown into position to stop or start the car, thus insuring that a person about to enter or depart from the elevator car or cage can readily see whether the floor of the car is flush with the floor of the landing or above or below the same, thus avoiding accidental injuries here- 80 tofore frequently occurring due to the inability of the passenger to clearly see the location of the car floor with respect to the landing floor.

Many electrical and mechanical equivalents for parts of the apparatus shown will readily suggest themselves to mechanics skilled in the art, and I therefore do not confine myself to the details of construction shown.

Having thus described my invention, I claim as new and desire to secure by Letters Patent:

1. A safety flash light system for an elevator car comprising a light adapted to flash 100 across the floor of the car at the gateway thereto, electrical connections for said light, and means, in combination with the operating lever of the car, for automatically lighting said light when the lever is thrown to 105 stop the car.

2. A safety flash light for elevators comprising in combination with the car-controlling lever, an electrical circuit normally open, an electric lamp connected in said circuit and positioned to throw its light out along the floor of the entrance to the car, magnetic means for making and breaking said light circuit, said magnetic means provided with circuit and circuit makers and breakers operated 110 by the car-controlling lever to complete said light circuit when the car is stopped and break the circuit when the car is put in motion.

3. A safety flash light for elevators, comprising in combination with the car-controlling lever an electric lamp, a normally open circuit for said lamp, magnetically operated means for closing said circuit, magnetically operated means for breaking said circuit, a 125 circuit closing means for closing the electric circuit through the magnet of said magnetic circuit closing means, when the car-controlling lever is brought to a position to stop the car, and a circuit closing means, for closing 130

the circuit through the magnet of said circuit breaking means, operated by said car-controlling lever when said lever is thrown to a position to put the car in motion.

5 4. A safety flash light for elevators comprising in combination with the car-controlling lever, of a normally open circuit, an electric lamp in said circuit and positioned to throw its light out along the floor of the car 10 through the gateway thereof, magnetically controlled circuit-closer means for said light circuit, means operated by said car-controlling lever to actuate said circuit-closer to

close said light circuit when the elevator car is stopped, and means operated by said car-controlling lever to actuate said circuit-closer to break said light circuit when said car is started. 15

In testimony whereof, I have hereunto set my hand at Los Angeles, California, this 28th 20 day of August, 1907.

CHARLES E. MOORE.

In presence of—

FREDERICK S. LYON,
FRANK L. A. GRAHAM.
